(57) **CLAIM**

The ornamental design for a storage accessory rail as shown and described.

DESCRIPTION

FIG. 1 is a front perspective view of the storage accessory rail;

FIG. 2 is a rear perspective view of the storage accessory rail of FIG. 1;

FIG. 3 is a front view of the storage accessory rail of FIG. 1;

FIG. 4 is a first side view of the storage accessory rail of FIG. 1;

FIG. 5 is a rear view of the storage accessory rail of FIG. 1;

FIG. 6 is a second side view of the storage accessory rail of FIG. 1;

FIG. 7 is a top view of the storage accessory rail of FIG. 1; and,

FIG. 8 is a bottom view of the storage accessory rail of FIG. 1.

The broken lines illustrate portions of the design that form no part of the claim.

1 Claim, 5 Drawing Sheets
